(57) **CLAIM**

The ornamental design for the exercise machine, as shown and described.

DESCRIPTION

FIG. 1 is a front, perspective view of an exercise machine showing the new design;

FIG. 2 is a rear, perspective view of the exercise machine;

FIG. 3 is a front elevation view of the exercise machine shown in FIG. 1;

FIG. 4 is a side elevation view of the exercise machine shown in FIG. 1;

FIG. 5 is a top plan view of the exercise machine shown in FIG. 1; and,

FIG. 6 is a bottom plan view of the exercise machine shown in FIG. 1.

The broken lines represent portions of the structure that form no part of the claim.
